UNITED STATES PATENT OFFICE

2,094,698

DEVICE FOR PACKING MATERIALS

James A. Flint, Upper Arlington, Ohio, assignor,
by mesne assignments, to The Traylor Vibrator Company, a corporation of Colorado

Application June 15, 1934, Serial No. 730,787
Renewed March 4, 1937

20 Claims. (Cl. 259—72)

This invention relates to a device for packing granular materials in receptacles or containers by imparting a vibratory motion thereto during the loading thereof and, although particularly adapted to the loading of such materials in barrels, it 5 may have a general application.

An object of the invention is the provision of a method of and means for firmly packing material in a container during loading thereof.

10 Another object of the invention is the method of and means for loading a container, such as a barrel, by imparting a vibratory motion thereto whereby the amount of material that may be placed in said container may be appreciably increased and the time required to fill the container may be appreciably decreased.

15 Other objects of the invention will appear hereinafter; the novel features and combinations being set forth in the appended claims.

20 In the accompanying drawings:

Fig. 1 is an elevational view of an improved form of my invention;

Fig. 2 is an end view of the mechanism of Fig. 1;

25 Fig. 2a is a sectional view on line 2a—2a of Fig. 2 looking in the direction of the arrows;

Fig. 3 is a sectional view on line 3—3 of Fig. 1 looking in the direction of the arrows;

Fig. 4 is an elevational view of another form of 30 my invention; and

Fig. 5 is an end view of the device shown in Fig. 4.

Referring particularly to Figs. 1, 2, 3, and 4 of the drawings, there is seen at 6, 6 a pair of stationary, permanently-fixed I-beams which comprise mounting means for the barrel packer of my invention. Each of said I-beams is provided with spaced upstanding bosses 7, 7 at the top thereof adapted to form seats for four coil springs 8, 8 which are adapted to yieldingly or flexibly support the vibratory structure of my invention.

A frame 11 is mounted on the coil springs 8, 8 by means of mechanism comprising the brackets 9, 9, provided with adjustable screws 9', 9' which are threaded vertically through the brackets 9, 9.

45 The lower end of each screw 9' extends into a recess in the top of cap 10 the lower side of which has a boss 10' to form a seat for the upper end of the spring 8. This provides an adjustable supporting of the frame 11 on said coil springs 8, 8 and allows any desired distribution of the weight of the whole device between said coil springs 8, 8.

50 As indicated in Figs. 1 and 3, the frame 11 is open at 12 adjacent one side thereof and is closed 55 at the opposite side 13. Said frame is provided

with a longitudinally extending opening 14 of a substantially rectangular cross-section.

Extending longitudinally through said opening 14 of the frame 11 is a plurality of stacked spring leaves 15 clamped rigid with said frame 11 at the 5 extreme ends of said spring leaves between downwardly projecting bosses 16, 16 at the top of said opening 14 and upwardly projecting clamp plates 17, 17 adjustable to clamping position by studs 18, 18. Intermediate the ends of said spring 10 leaves 15, the upper and lower walls of frame 11 are spaced therefrom to allow free vibration thereof about their clamped ends.

Within the opening 12 of the frame 11 there extends an upright armature shaft 19 provided 15 with a transverse rectangular opening 20 through which said spring leaves 15 are adapted to extend and be clamped to said armature shaft at their center points by means of a clamping plate 21 forcing the spring leaves downwardly against 20 the bottom of said opening 20 under the influence of clamping studs 22, carried by a transverse web 22'.

25 The clamping plate 21 may be provided with a machine screw 23 surrounded by a coil spring in 25 which the shank of the machine screw extends loosely through said transverse web 22' and is screw-threaded into clamping plate 21. By this means, the clamping plate 21 is held in place by the machine screw 23 prior to the insertion of the 30 spring leaves 15.

The armature shaft 19 is provided with a cross head 24 formed integral therewith, adapted to carry a supporting bed frame 25 as by nuts and bolts 26, 26. The bed frame 25 comprises a substantially horizontal plate 27 and parallel downwardly extending plates 28, 28, the latter being adapted to be clamped to the cross head 24 by nuts and bolts 26, 26. Reinforcing webs 29 may be provided to reinforce the horizontal plate 27. Said plate 27 is preferably provided adjacent each of its ends with upwardly extending barrel guides 30 adapted to position the barrels 31 during the filling thereof.

At its lower face, frame 11 is provided with 45 spaced U-shaped brackets 32, 32 clamped at their upper ends to said frame 11 as by studs. Between the bottoms of said U-shaped brackets is adjustably mounted an electric motor comprising a field structure 33 having a U-shaped field 50 core of magnetic material, as iron or steel laminations, and a field winding. The field winding is adapted to be energized from any source of alternating or pulsating current as, for example, the ordinary commercial outlet providing 60- 55

cycle alternating current. It is, of course, understood that current of any frequency may be employed provided the hereinafter discussed relation is maintained.

5 The lower end of the armature shaft 19 is adapted to carry an armature 33' preferably comprising iron or steel laminations 34 and adapted to be spaced from the core of said field structure 33 to form an air gap therewith and to 10 vibrate with respect thereto when said field winding is energized by alternating or pulsating current.

15 It is thus seen that the barrels 31 to be filled with material are supported on a vertically vibrated vibratory structure designated generally by 37 and comprising said armature 33', armature shaft 19, cross head 24, bed frame 25, plate 27 and all parts rigid with any of the specifically mentioned elements thereof. This vibratory structure 37 is in turn supported by means of spring leaves 15 at their center points, which spring leaves are supported by the frame 11 at their extremities. The field structure 33 of the electric motor is rigid with the frame 11, being 20 rigidly attached thereto by said U-shaped brackets 32, 32. The frame 11 is also flexibly supported by the springs 8, 8 to prevent the transfer 25 of any vibratory movement of said frame 11 to the I-beams 6, 6.

30 The amplitude of vibration of said armature 33' and the resulting amplitude of vibration of the vibratory structure 37 may be adjusted within limits by controlling the width of the air gap between the armature 33' and the core of the field structure 33 by the adjustable screws 35, 35 which are screw-threaded through the bottom of the U-shaped brackets 32, 32 and carry between the adjusting nuts 36, 36 a top plate of the field structure 33.

40 In addition, the amplitude of vibration of armature 33' may be controlled by inserting a variable resistor in the circuit of the field coil of said field structure 33 to control the current flow therein and consequently control the magnetic 45 strength thereof.

45 In the operation of my device, the armature 33' is attracted toward the field structure twice during each complete cycle of energization of said field structure 33 when the latter is energized by 50 alternating current; that is, if the field structure 33 is energized by a current of a frequency of sixty cycles a second, the armature 33' will be attracted one hundred twenty times a second. During each attraction of the armature 33', the 55 vibratory structure designated generally by 37 is adapted to vibrate. This vibratory action is effected by the spring leaves 15 and the vibratory motor comprising the field structure 33 and the armature 33'. That is, during each attraction of 60 the armature 33' by the field structure 33, the armature shaft 19 is moved downward and deflects the spring leaves 15, storing energy therein. Upon the reduction of current flow in the field winding of the field structure 33, the armature 33' is effectively released whereupon the vibratory structure 37 is moved upward under the influence of the spring leaves 15, which tend to 65 assume their initial positions and therefore transfer the energy stored therein by their deflection 70 to said vibratory structure 37.

75 In order to enhance greatly the effectiveness of my device and to reduce greatly the amount of energy required to perform a packing operation, it is particularly desirable that the vibratory system have a natural period of vibration

which is nearly the same as the period of operation of said armature 33' under the influence of the field structure 33. That is, if the field structure 33 is energized by alternating current of 60-cycle-per-second frequency and attracting 5 the armature 33' at a frequency of one hundred twenty times a second, then the natural period of vibration of said vibratory structure should be approximately one hundred twenty cycles per second. The period of vibration of said 10 vibratory structure may be determined by well-known mechanical formulae.

While it is preferred that the natural period of vibration of said vibratory structure 37 be substantially the same as the period of energization 15 of the field structure 33, it is desirable that exact resonance between the two be not maintained. It is therefore preferable to have the period of the vibratory structure either slightly below or slightly above the period of energization 20 of the field structure 33 whereby there is always some load upon the motor vibrator comprising the field structure 33 and the armature 33'. In the absence of some load upon said motor vibrator, it is difficult to control and will tend to 25 destroy itself when no useful work is being done.

In addition, by operating the device at a frequency slightly different from its natural frequency, the amplitude of vibration of the vibratory structure 37 will be substantially constant, irrespective of the load carried on the plate 27. This is of considerable advantage because the vibratory action received by the granular material fed to the barrels 31 will be substantially the same when the filling operation begins as 35 when it ends. Uniform packing throughout the barrels is thus insured.

It is also an important characteristic of my device that the load provided by the barrels 31 does not alter the natural period of vibration 40 of the vibratory structure 37. This is apparently due to the high frequency of vibration thereof, 7200 cycles per minute when energized from a commercial source of 60-cycle per second current, which results in the barrels 31 acting as 45 a "live" load, rather than a "dead" load, relative to said vibratory structure 37. That is, the barrels 31 do not become an effective part of the vibratory structure 37. As a consequence the vibratory period of said structure 37 may be pre-selected at a value slightly above or below the period at which it is to be vibrated and this difference will be substantially constant regardless of the amount of material in barrels 31. It has been demonstrated by experiment on an average 55 size device that the natural period of the vibratory structure 37 alone is substantially unaltered by the presence of filled barrels 31 weighing over a hundred pounds, while the clamping of a weight of as small as ten pounds rigid with 60 said vibratory structure 37 definitely alters its natural period. While a frequency of 7200 cycles per minute is mentioned, it is to be understood that considerably lower frequencies are also employed with the same general characteristics, 65 said frequencies being as low as 1500 cycles per minute. However, even this frequency is a "high frequency" as understood in this art and as herein claimed.

70 By employing the packing device embodying my invention, a wide range of materials, particularly of granular nature, may each be uniformly packed. For instance, chemical salts may be uniformly packed in given sized containers so that 75

when filled each will hold a predetermined amount in the space available.

By employing my invention, the time necessary to pack a given size container uniformly with a predetermined amount of material may be very materially reduced. In addition, it has been found in practice that the amount of material which may be packed into a container is very materially increased. Packing of granular material may therefore be efficiently effected in measured quantities in cartons of reduced size.

In Figs. 4 and 5 I have illustrated another form of my invention which does not differ greatly from that illustrated in Figs. 1, 2, and 3. The differences in structure from said form illustrated in Figs. 1, 2, and 3 will be particularly discussed. In the form of my invention as illustrated in Figs. 4 and 5, the horizontal plate 27' is designed to carry a single retainer 31. The frame 11' in which the spring leaves 15' are mounted is not open at one side as was the frame 11 but, as seen in plan view, comprises a continuous ring with a central opening for receiving the armature shaft 19'. The mounting of the frame 11' differs from that illustrated in Figs. 1, 2, and 3. Said mounting comprises upright standards 38, 38 with feet 39, 39 adapted to rest upon the floor or foundation. The upper ends of said standards 38, 38 are provided with cups 40, 40 adapted to receive spring means which may comprise rubber cylinders 41, 41 having central openings 42, 42 adapted to receive guide pins 43, 43 carried on brackets 44, 44 rigidly attached to frame 11'. Said rubber cylinders 41, 41 thereby restrict the transfer of vibrations from the frame 11' to the standards 38.

In each of the forms of my invention, it is desirable that the vibrations of the motor vibrator 33' be imparted as much as possible to the vibratory structure 37 and that a minimum of vibration be imparted to the frame 11 or 11'. To this end the weight of said frame 11 or 11' is made substantially greater than that of the vibratory structure 37 and is preferably at least twice the weight thereof. By this expedient, the vibrations are manifest principally by the vibratory structure 37 and to only a small degree in the frame 11 or 11'. Such vibrations as are present in the frame 11 or 11' are not transmitted to the supporting structure 6 or 38 by virtue of the spring mountings 8 and 41.

The amplitude of vibration of the vibratory structure 37 is so small and its rate of vibration so large that the vibratory movement thereof is not visible to the naked eye but is sensitive by touch and is very effective to produce the desired packing operation.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. In a vibratory barrel packing device, the combination with a vibratory structure including a container support of sufficient size to support a large container, like a barrel, and carried upon energy storing springs, said structure having a natural period of vibration independent of any container supported thereby, of vibratory motor means for periodically storing energy in

said springs by causing deflection thereof and for periodically releasing said springs whereby they may vibrate said body by said stored energy, said motor means operating at a frequency near to but slightly different from the natural period of said vibratory structure.

2. In a vibratory packing device, the combination with a vibratory structure including a container support, of means comprising a spring leaf for supporting said vibratory structure, said vibratory structure having a natural period of vibration, and means for vibrating said vibratory structure at a frequency slightly different from said natural period.

3. In a vibratory packing device, the combination with a vibratory structure including a container support adapted to support a heavy container, of carrying means for said vibratory structure comprising a spring leaf attached thereto at its center and rigidly attached to a supporting frame at each end for periodically imparting vibratory motion to said vibratory structure by energy stored therein, and vibratory motor means for periodically storing energy in said spring leaf by deflection thereof at a rate of 7200 cycles per minute when energized by current of a frequency of 60 cycles per second.

4. In a vibratory packing device, the combination with a vibratory structure including a container support, of carrying means for said vibratory structure comprising a spring leaf attached thereto at its center and rigidly attached to a supporting frame at each end, said spring predetermined the natural period of vibration of said vibratory structure, and motor means for periodically vibrating said vibratory structure at a high frequency and slightly different from said natural period.

5. In a vibratory packing device, the combination with a vibratory structure comprising means adapted to carry a container to be filled with material, of carrying means for said vibratory structure comprising a spring leaf attached thereto at its center and rigidly attached to a supporting frame at each end, said spring predetermined the natural period of vibration of said vibratory system at a high frequency and independent of the weight of said container, and motor means for periodically vibrating said vibratory structure at a frequency slightly different from said natural period and at a high frequency, said supporting frame having a weight at least twice as great as that of the vibratory structure.

6. In a vibratory packing device, the combination with a vibratory structure comprising means adapted to carry a large container to be filled with granular material, of carrying means for said vibratory structure comprising a spring leaf attached thereto at its center and rigidly attached to a supporting frame at each end, said spring predetermined the natural period of vibration of said electric vibratory system, electric motor means comprising an armature as a part of said vibratory structure for periodically vibrating said vibratory structure at a frequency slightly different from said natural period and at a frequency of 7200 cycles per minute when energized from a source of current of 60 cycles per second.

7. In a vibratory packing device, the combination with a vibratory structure comprising means adapted to carry a container to be filled with granular material, of carrying means for said vibratory structure comprising a spring leaf attached thereto at its center and rigidly attached

to a supporting frame at each end, said spring predetermining the natural period of vibration of said vibratory system, electric motor means comprising an armature as a part of said vibratory structure for periodically vibrating said vibratory structure at a frequency slightly different from said natural period, said supporting frame having a weight at least twice as great as that of said vibratory structure.

8. In a vibratory packing device, the combination with a vibratory structure comprising means adapted to carry a container to be filled with granular material, of carrying means for said vibratory structure comprising a spring leaf attached thereto at its center and rigidly attached to a supporting frame at each end, said spring predetermining the natural period of vibration of said vibratory system, and electric motor means comprising an armature as a part of said vibratory structure for periodically vibrating said vibratory structure at a frequency slightly different from said natural period, said motor being adapted to impart vibratory movement to said vibratory structure substantially entirely along a vertical axis and at a frequency at which the container acts as a live load on said vibratory structure and does not affect the predetermined frequency thereof.

9. In a vibratory packing device, the combination with a vibratory structure including a container support, of carrying means for said vibratory structure comprising an energy storing spring leaf attached thereto at its center and rigidly attached to a supporting frame at each end thereof, said spring predetermining the natural period of vibration of said vibratory system, and motor means for periodically storing energy in said spring by causing deflection thereof and for periodically releasing said springs whereby they may vibrate said body by said stored energy, said motor means operating to deflect and release said spring at a frequency substantially the same as the natural period of said vibratory structure.

10. In a vibratory packing device, the combination with a plate adapted to carry a plurality of containers to be filled with material, of means for suspending said plate for vibration comprising a central support, a leaf spring attached to said central support at its center and attached to a frame at each end thereof, said spring being capable of supporting heavy weights without appreciable deflection, and electro-magnetic means for imparting high frequency vibratory motion to said plate along an axis parallel with the axis of said support thereby to deflect said spring periodically under the cumulative influence of electric impulses.

11. The method of packing material comprising supporting the material on a vibratory structure having a natural period of vibration and carried on energy storing springs, periodically deflecting and releasing said springs at a period substantially in resonance with the natural period of said vibratory structure whereby energy is periodically stored in said springs and delivered up by said springs to vibrate said vibratory structure at approximately its natural frequency.

12. The method of packing granular material which consists in supporting such material on a vibratory structure having a natural period of vibration and carried on energy storing springs which springs are in turn supported by a frame of weight at least twice as great as the weight of the vibratory structure, imparting vibrating forces to said vibratory structure by periodically deflect-

ing and releasing said springs at such frequency as has a period substantially in resonance with the natural period of said vibratory structure whereby energy is periodically stored in said springs and delivered up by said springs to vibrate said vibratory supporting structure at approximately its natural frequency. 5

13. The method of packing material comprising supporting the material on a vibratory structure having a natural period of vibration and carried on energy storing springs, periodically deflecting and releasing said springs at a period slightly different from the natural period of said vibratory structure whereby energy is periodically stored in said springs and delivered up by said springs 15 to vibrate said vibratory structure at a frequency slightly different from its natural frequency.

14. The method of packing material comprising supporting the material on a vibratory structure having a natural period of vibration which 20 comprises imparting vibratory movement to said structure at a frequency slightly different from its natural period, whereby vibrations of substantially uniform amplitude will be imparted thereto regardless of the amount of material being 25 packed, with a minimum expenditure of energy.

15. The method of packing granular material in a container, comprising supporting the container on a vibratory structure having a natural 30 period of vibration and while gradually delivering the granular material to said container imparting vibratory movement to said structure at a frequency differing from its natural period to enable maintenance of such vibrations at uniform amplitude until said container is completely filled. 35

16. The method of packing granular material in a container which consists in imparting to the support for the container electro-magnetic impulses by means of uninterrupted undulating electric current having a frequency differing from 40 the natural period of vibration of said support and thereby maintain a uniform amplitude of vibration with a minimum expenditure of electric current until the container is compactly and quickly filled with such granular material. 45

17. The method of quickly and compactly packing granular material in a container, which consists in imparting to a resilient support for the container electro-magnetic impulses by means of uninterrupted undulating electric current having 50 a frequency differing from the natural period of said support and maintaining a substantially uniform amplitude of vibration with a minimum expenditure of such electric current during such filling of said container. 55

18. The method of quickly and compactly filling a container with granular material which consists in imparting vibrations of minute amplitude to a resilient support having only extremely small flexure and a natural period of vibration by means of uninterrupted undulatory electric current to exert electro-magnetic impulses on such support at a frequency different from said natural period to effect maintenance of the aforesaid amplitude while granular material is gradually delivered to 60 said container.

19. The method of quickly and compactly filling a barrel with granular material which consists in imparting to a slightly yielding barrel support during the gradual filling of the barrel thereon vertical vibrations of minute amplitude by means of uninterrupted undulating electric current to exert on said support electro-magnetic impulses having a frequency differing from the natural period of said support thereby maintaining sub- 70 75

stantially uniform such amplitude of vibration with a minimum consumption of electric current during the entire time consumed for the complete filling of said barrel with said granular material.

5 20. A vibratory packing device, comprising the combination with a plate adapted to carry a container to be filled with material, of means for supporting said plate for vibration comprising a central support, a leaf spring attached to said

central support at its center and attached to a frame at each end thereof, said spring being capable of supporting heavy weights without appreciable deflection, and electro-magnetic means constructed and arranged to impart high frequency vibratory motion to said plate by deflecting said spring periodically under the cumulative influence of electric impulses.

JAMES A. FLINT.
